[57] CLAIM

The ornamental design for an elastic pistol grip cover, as shown and described.

DESCRIPTION

FIG. 1 is a view of one side of the design showing it related to a pistol and is a mirror opposite of the other side thereof;

FIG. 2 is a front view of the design;

FIG. 3 is a rear view of the design;

FIG. 4 is a top view of the design; and,

FIG. 5 is a bottom view of the design.

The broken line showing of a pistol in FIG. 1 is for illustrative purposes only and forms no part of the claimed design.
